UNITED STATES PATENT OFFICE.

WILLIAM KING RICHARDSON, OF LEAVENWORTH, KANSAS.

CENTRIFUGAL PUMP.

1,080,655.

Specification of Letters Patent.

Patented Dec. 9, 1913.

Application filed September 3, 1912. Serial No. 718,342.

To all whom it may concern:

Be it known that I, WILLIAM K. RICHARDSON, a citizen of the United States, residing at Leavenworth, in the county of Leavenworth, State of Kansas, have invented a new and useful Improvement in Centrifugal Pumps, of which the following is a specification.

The object of my invention is to eliminate the liquid friction of the impeller. Whether the pump is of volute type or employs diffusion vanes, liquid friction is a source of loss in both head and power, and when high velocities are employed the loss becomes excessive. This source of loss is due to the fact that the volute or whirlpool chamber and the diffusion vanes are stationary, and therefore impact and velocity of flow of this surface is lost energy. To overcome this defect, I employ the principle that two rotary surfaces of like area and coefficient of friction, rotating in the same direction, but at different speeds, having a perfect fluid interposed, the high speed disk will incur no greater resistance due to friction of the fluid, than the impetus the fluid will impart to the low speed disk through its frictional contact. The friction of the high speed disk imparts kinetic energy to the water, and the flow of the water over the surface of the low speed disk tends to drive it ahead with the same force as the resistance it offers to the high speed disk. Illustration: The sq. root of one-half of the sum of the squares of the velocity of the two revolving disks, equals the velocity of the water interposed between the disks. To determine the moments of friction resisting the high speed disk and the impulse received through frictional contact of the water passing over the low speed disk, it is expressed thus: The sq. of the velocity of the high speed disk minus the sq. of the velocity of the water equals the moment of friction for the high speed disk. The sq. of the velocity of the water interposed between the disks minus the square of the velocity of the low speed disk equals the impetus or moment of friction upon the low speed disk, and at all speeds they are found to be equal.

In carrying out my invention in either a single or multiple stage pump, the high speed impeller discharges at its periphery, and the water enters an adjacent low speed rotor at its periphery, and discharges at the eye of the runner. The kinetic energy of the

water due to the high speed runner is thus checked, and the energy absorbed by the low speed runner through impact and friction of the water is conveyed back to the driving shaft by suitable means. The relative velocity of the high and low speed runners will vary according to the type and service of the pump. It being understood the lower the speed of the low speed runner, the higher the efficiency of the pump, because the water is under less centrifugal force due to the rotary motion of the low speed runner. Illustration: Should the high speed runner make five revolutions to one revolution of the low speed runner, the loss in effective head will be 4%. If their speeds are two to one, the loss will be 25%, for the centrifugal effect of the runners are as the squares of their respective velocities or number of revolutions.

In my construction a revolving casing encompasses the runners and is preferably attached to the low speed runner.

The object of this invention is to produce a centrifugal pump of high efficiency, of broad utility, a machine that may be direct connected to any prime mover, or belt driven, and that may be produced by the manufacturer at a cost no greater than the average cost of pumps of turbine type. With these objects in view my invention consists in the construction and combination of parts as hereinafter described and claimed, of which:

Figure 1 is a vertical cross section of a three-stage centrifugal pump embodying the principles of my invention. Fig. 2 is an end view of the intake side of Fig. 1, the intake and journal bearing not being shown in Fig. 1, but in construction is the same as the discharge end. Fig. 3 is a vertical cross section of a single stage pump showing the construction employed in carrying out my invention. Fig. 4 is an end view of the intake side of the single stage pump. Fig. 5 is a plan view of a segment of the roller cage 38, showing the rollers 39 mounted therein. Fig. 6 is a plan view of the bifurcated race 43. Fig. 7 is a plan view of the low speed runner 14, with a portion of the face plate 15 removed. Fig. 8 is a plan view of the high speed runner 8, with a portion of the face or driving plate 10 removed.

1 indicates a base plate to which is bolted standards 2 and 3.

4 indicates a journal bearing secured to each standard for the reception of shaft 5.

6, 7 and 8 indicate high speed runners, of which 6 and 7 are annular disks centrally perforated and key-seated to the shaft 5. They are turned to like diameters, and machined on face and back, and on the face of each runner is cast integral vanes or fins 9, their radial length and pitch being clearly shown in Fig. 8, the bolt boss being omitted as therein shown.

10 indicates a driver, the same being an annular disk centrally perforated and secured to shaft 5, said driver being bolted to the runner 8. The runner 8 is an annular disk having a central hollow hub 11, the back of the runner being convex and on the face or concave side are cast integral vanes or webs 9 as shown in Fig. 1.

12, 13 and 14 indicate low speed runners, having face plates 15. Runners 12 and 13 are annular disks having a central opening of the same diameter as the opening in hub 11. On one side is cast integral curved vanes or fins 16, as shown in Fig. 1, and to these vanes is bolted the face plate 15, the same being an annular disk centrally perforated and journaled on shaft 5. The periphery of the runners 12 and 13, is of greater diameter than the vane 16, and when the runners 12, 13 and 14 are bolted to the cylindrical runner 17, the race chambers 18, 19 and 20 are formed.

The low speed runner 14 has vanes and a face plate similar to those of runners 12 and 13, excepting they do not so nearly approach the center, as shown in Fig. 1, and which will be hereinafter be explained. The runner 14 performs the double function of a low speed runner and an end casing to the impeller, being secured to the member 17 as shown in Fig. 1.

21 indicates a sleeve bolted to member 16 and provides a discharge passage from the impeller to the discharge port 22. The outer end of sleeve 21 is provided with a stuffing box and gland 23.

24 is an end casing of the impeller bolted to member 17, and bolted to the inner side 50 of member 24, and surrounding hub 11 is a cup packing 25.

26 indicates a spur-wheel bolted to the member 24. 27 indicates a pinion secured to the hub 11.

55 indicates a liquid packing gland, of which *a* indicates a central perforated disk secured to the hub 11, which rotates in the chamber *b*, formed by a casing *c*, attached to standard 2, the casing *c* being provided 60 with a cup packing *D*.

In the eye of each of the high speed runners 6, 7 and 8, is placed a screw 29, said screw consisting of a central web forming a sleeve of a diameter sufficient for the reception of shaft 5. To the sleeve is cast

projecting helical blades, their angular pitch being opposite to the direction of rotation. The purpose of these screws need not be particularly described in this specification, as this feature will form the subject matter of a separate application for patent. 70

30 indicates the intake, a portion of which is not shown. In construction it is the same as discharge port 22, but of greater area of cross-section. 31 indicates a standard for the support of a gear shaft 32, one end of said shaft being journaled in shaft box 33 attached to standard 2. Upon said shaft 32 are mounted and keyed spur wheel 34 and pinion 35. (The gear 26, and pinion 35 should have twice the face shown, and when the pump is designed for high heads the H. P. of the gear should be strong enough to transmit the power due to liquid friction upon the revolving casing and the low speed runners, and the impact of the water.) 85 These gears control the relative speeds of the rotors.

Having thus designated the several parts of this machine, the following is a description of the operation: When the suction pipe (not shown), which is provided with the usual foot valve at the source of supply, is connected to the intake 30, and the pump primed in the usual way, the driving power is applied to shaft 5, the driving pulley or coupling (not shown) may be disposed at either end of the shaft. To reduce the torque of the machine, the discharge should be throttled until the normal speed is attained. The water under suction enters the intake 30 and is subjected to centrifugal force and the repulsive action of the screw 29. Before the water enters the chamber of the high speed runner 8, it has acquired 95 rotary motion and an absolute pressure exceeding the pressure of the water at the bit of the screw. As the water enters the chamber of runner 8, it is subjected to a constant increasing centrifugal force in its radial flow 100 by the vanes 9, and is discharged into the race chamber 18, under the maximum or theoretical head. Some of the rotary velocity is here checked, due to friction but such loss of kinetic energy of the water is 105 communicated to the slow revolving casing. As the water enters the chamber of the low speed runner 12, its rotary velocity is checked by the cycloidal vanes 16, the energy 110 due to the impact of the water upon the vanes of this runner tending to rotate it at a velocity equal to the velocity of the impinging water, but owing to the speed reducing gear, the casing to which the low speed runner is attached makes but one revolution to five revolutions of the high speed runner. The spur wheel 26, attached to member 24 of the casing, transmits the energy to the pinion 35, and this impulse is 115 transmitted through the medium of spur 120

125 gear 26, and pinion 35, and this impulse is transmitted through the medium of spur 130

wheel 34 to the pinion 27 which is attached to the hollow hub 11 of the high speed driver 8, the same being rigidly attached to shaft 5 as previously described. The loss of effective head, when the water reaches the eye of the low speed runner, will be the centrifugal force the water is subjected to by the low speed impeller, and the ratio of loss will be as the sq. of the number of its revolutions or angular velocity to the sq. of the number of revolutions or angular velocity of the high speed runner, and in the machine herein described is as one to twenty-five, or 4%.

15 The space intervening between the face plate of the low speed and the high speed runners is occupied by a racing fluid, and as both plates rotate in the same direction there can be no loss of power due to friction because the frictional resistance of the fluid to the high speed disk just equals its velocity friction impelling the low speed disk.

15 The slight rotary velocity the water retains as it passes from the low speed runner 12 to the adjacent high speed runner 12, is accelerated by the screw 29 and as the water enters the chamber of runner 7 under hydraulic head, it is again subjected to centrifugal force, and when discharged into race chamber 19, has a head twice that at the eye of the runner. It will be noted that the high speed runner 7 has no face plate. This construction avoids slippage that 35 would take place if a face plate were used, for the difference in pressure between the eye and the discharge end of the runner could not be compensated or balanced by the rotary velocity of the fluid between the plates, and a back flow would take place 40 from the race chamber to the eye of the runner between the plates, because the centrifugal force of the water between the plates will only slightly exceed one-half the 45 centrifugal force within the chamber of the runner. Therefore, there would be an induced flow between the plates under a head equal to one-fourth the hydraulic head in 50 chamber 19. In the construction shown no slippage takes place, because the full centrifugal force of the water at any radial point exerts a corresponding lateral pressure upon the back of runner 12, and as previously described, any friction of the fluid 55 that tends to retard the high speed runner, the same force must be communicated to the low speed runner rotating in the same direction.

When the water has passed through all 60 the runners constituting the stages of the pump, it is forced through discharge passage 22. As the machine shown and described employs positive gear transmission between the low speed casing and the high 65 speed runner or driving shaft, a thrust bear-

ing 36, and a set collar 37 is provided at the end of the journal bearing 4 to receive the end thrust.

Fig. 3 represents a structure embodying my invention as employed in a single stage 70 pump. The difference in this construction from the multiple stage pump being in providing a suitable journal bearing for the low speed runner 14, and the revolving casing, and the employment of a friction drive. 75 Referring to Fig. 3 and Fig. 5, 38 indicates a roller cage, in which are mounted the frusta of cones 39, upon hollow journals 40. 41 indicates a thrust bearing journaled upon member 40, and interposed between the outer end of each cone and a boss cast integral with the cage 38 as clearly shown in Fig. 5. 42 indicates a driven wheel secured to member 11. 43 indicates a bifurcated driving race secured to standard 2. The cone 39 has three 80 roller surfaces of which a' indicates that portion of the rolling surface at the base of the frustum. b' indicates the rolling surface between the surfaces a' , and c' , c' designates the rolling surfaces next to the apex 85 of the frustum. c' and a' have the same face angle, that angle being determined by the radius of the race 43 upon which they run, and the diameter of the rolling surface at the base of the frustum. The rolling surface b' is of greater diameter than a' or c' and is determined by the relative speeds the high and the low speed runners are to maintain. 46 indicates an annulus or pulley bolted to member 24 which encompasses the 100 roller cage 38, said cage being provided with dowel pins 47 as shown in Fig. 5. These pins extend through holes in the rim of the annulus 46, said holes being large enough to permit of some freedom of lateral motion. 105 The face plate 15 has a hub cast integral therewith to form a journal bearing, as shown in Fig. 3. Interposed between the low speed runner 14 and the high speed runner 12 is a thrust bearing 38, as the end 110 thrust is imposed upon the low speed runner the employment of a thrust bearing is required. 49 indicates a driving pulley that may be employed in place of the friction drive heretofore described, it being understood that when this driving pulley is employed, a smaller pulley will be attached to the driving shaft. 50 indicates a compression spring interposed between a ball bearing 51 and a set collar 52 mounted on shaft 5, and is used for the purpose of increasing the stress upon the friction rollers when this gear is employed, and especially, when the pump is operating against moderate heads but handling a larger volume of water.

115 The operation of the friction drive is as follows: It being understood that the shaft and high speed runner make five revolutions to one revolution of the low speed runner and casing, as shown in this construction.

The rotation of the casing through members 46 and 47 imparts motion to the roller cage, causing the cones 39 to roll upon the bifurcated race 43. The travel of the rolling surface *c'* of the cone is exactly the same as the race upon which it runs, and that tendency of the casing to rotate at a speed equal to the velocity of the high speed runner imparts its kinetic energy to member 42 and 10 then to the driving shaft.

Having thus described my invention, what I claim as new and desire to secure by Letters Patent, is—

1. In a machine whose operation involves 15 a moving fluid, the combination with a high speed driven rotor and a low speed fluid actuated rotor operating in the same direction and arranged to receive fluid delivered from said high speed rotor, said rotors having a fluid interposed between them, of a rotary casing inclosing said rotors and attached to one of them, and means for maintaining constant the relative speeds of said rotors.

25 2. In a machine whose operation involves a moving fluid, the combination with a driven element from which fluid in motion is delivered, of a structurally independent fluid actuated mechanism operated by the 30 kinetic energy of the fluid due to friction, and also by the fluid delivered from the driven element and from which fluid is delivered under pressure, means for transmitting power from said fluid actuated mechanism and for maintaining constant the relative 35 speeds of said elements.

3. In a centrifugal machine, the combination with a high speed rotor from which fluid under motion and pressure is delivered, 40 of a low speed fluid actuated rotor operated by the fluid so delivered and from which fluid is delivered under pressure, a rotary casing inclosing said rotor elements and attached to one of them, and positive means 45 for transmitting power engendered by the kinetic energy of the fluid in contact with

the fluid actuated rotor to the driving mechanism of the high speed rotor.

4. In a machine whose operation involves 50 a moving fluid, the combination with a high speed driven rotor fixed upon a shaft, a low speed fluid actuated rotor journaled upon said shaft and operating in the same direction and arranged to receive fluid delivered from said high speed rotor and having a 55 fluid interposed between them, a rotary casing inclosing said rotors and attached to one of them, and means for maintaining constant their relative speeds.

5. In a machine whose operation involves 60 a moving fluid, the combination with a set of driven rotors from which fluid in motion is delivered, of a set of fluid actuated rotors alternately arranged with respect to the driven rotors, and operated by the fluid so 65 delivered, a rotary casing inclosing said sets of rotors and secured to one set of them, and means for connecting said casing and the other set of rotors to the driving mechanism of the driven rotors and maintaining 70 constant the relative speeds of said sets of rotors.

6. In a machine whose operation involves a moving fluid, the combination with a set of driven rotors from which fluid in motion is delivered, of a set of fluid actuated rotors alternately arranged with respect to the driven rotors and operated by the kinetic energy of the fluid due to friction, and also by the fluid delivered from the driven rotors 80 and from which fluid is delivered under pressure, a rotary casing inclosing said rotary elements and secured to one set of them, and means for connecting said casing and the other set of rotors to the driving 85 mechanism of the driven rotors and for maintaining constant the relative speeds of said sets of rotors.
